United States Patent Office

Des. 198,434
Patented June 16, 1964

198,434

SCOURING PAD HOLDER

Irwin Miller, 180 Linden St., New Haven, Conn., and Alfred W. Wakeman, Madison Road, Durham, Conn.

Filed Feb. 18, 1963, Ser. No. 73,617

Term of patent 14 years

(Cl. D9—2)

FIG. 1 is a perspective view of a scouring pad holder embodying our new design;

FIG. 2 is a right side elevational view thereof, the opposite side being a mirror image thereof;

FIG. 3 is a front elevational view thereof;

FIG. 4 is a rear elevational view thereof; and

FIG. 5 is a sectional view taken along line 5—5 of FIG. 3.

We claim:

The ornamental design for a scouring pad holder, as shown and described.
